SERVICE CONNECTER

George J. Meuer and Ralph A. Millermaster,
Milwaukee, Wis., assignors, by direct and mesne
assignments, of one-half to Cutler-Hammer,
Inc., Milwaukee, Wis., a corporation of Dela-
ware, and one-half to Borg-Warner Corpora-
tion, a corporation of Illinois

Application July 16, 1934, Serial No. 735,443

6 Claims. (Cl. 173—324)

This invention relates to improvements in service connectors for electrical devices and more particularly to improvements in service connectors for electric refrigerators.

The various electrical devices employed in an electric refrigerator, including the compressor motor and its temperature responsive automatic control and a lamp for illuminating the interior of the refrigerator upon opening the refrigerator door, present a problem in providing a simple and convenient arrangement for connecting the same to a source of current supply. Connector devices have been proposed having terminal elements to provide for connection of a pair of wires to the positive and negative lines, respectively, of a current supply source. In order to connect the electrical devices to the current supply it is necessary to splice the separate wires from each of the devices to the two wires of the connector, necessitating the inconvenience and inefficiency of splicing, soldering and taping these connections. These spliced connections may be more or less widely separated, or if, as has been proposed, a recess is provided in the cord receiving end of the connector to accommodate the taped connections, the splicing, soldering and taping is required to be accomplished in a limited space, making these operations and the insertion of the knot of taped wires into the connector very awkward and inefficient. In either case, the connections are potential sources of trouble, due to faulty splicing or other causes, which are difficult to trace.

An object of the present invention is to provide a connector device which will overcome the aforementioned disadvantages and difficulties.

Another object is to provide a device of the aforementioned character in which terminal elements are provided, such terminal elements being so combined and related as to provide for convenient connection of all of the electrical devices of a refrigerator to a current supply source and/or to each other without the necessity for spliced connections.

Another object is to provide a connector device which is simple and inexpensive in construction.

Another object is to provide a connector device having parts constructed and arranged to facilitate assembly thereof.

Another object is to provide a connector device having terminal and contact elements of improved and simplified construction.

Various other objects and advantages of the invention will hereinafter appear.

The accompanying drawings illustrate certain embodiments of the invention which will now be

described, it being understood that these embodiments are susceptible of modification without departing from the scope of the appended claims.

In the drawings, Figure 1 is a plan view of the contact blade and cord receiving end of a connector embodying our invention. 5

Fig. 2 is a plan view of the inner end of the base portion of the connector shown in Fig. 1, showing the arrangement of the terminal elements thereon.

Fig. 3 is a plan view of the lamp receiving end of the connector. 10

Fig. 4 is a perspective view of the connector with parts thereof broken away for purposes of illustration; a typical refrigerator electrical system being shown diagrammatically in connection therewith to illustrate the manner in which the same is employed. 15

Fig. 5 is a section on line 5—5 of Fig. 1.

Fig. 6 illustrates the manner of attachment of the connector shown in Figs. 1 to 5 to a refrigerator motor control casing. 20

Fig. 7 is a plan view of the cord receiving end of a modified form of connector embodying our invention. 25

Fig. 8 is a section on line 8—8 of Fig. 7.

Fig. 9 illustrates diagrammatically a refrigerator electrical system similar to that of Fig. 4, showing the manner of employment of the connector illustrated in Figs. 7 and 8, one part only 30 of the two part insulating casing of said connector being shown for purposes of illustration.

Fig. 10 is a section on line 10—10 of Fig. 8.

Fig. 11 is a flat development of a lamp screw shell and of the ring type lamp contact used in 35 the connector shown in Figs. 1 to 6, inclusive.

Figs. 12, 13 and 14 are views partly in elevation and partly in section, showing the manner of cooperation between the ring contact and the threads of the lamp screw shell; the sections of 40 the ring being taken on lines 12—12, 13—13 and 14—14, respectively, of Fig. 11.

Referring to Figs. 1 to 6 of the drawings, the numeral 1 designates a connector, the parts of which include a molded insulating base 2 of cylindrical form. Said base is provided in its outer face with a circular recess 3 which is of reduced diameter at its inner end, forming an annular shoulder 4 substantially midway between the outer end and the bottom wall of said recess. 45 Adapted to seat within the recess 3 upon the diametrically opposed outwardly projecting bosses 5 and 6 on the annular shoulder 4 is a punched sheet metal, ring-shaped contact member 7. The inner edge of the ring 7 is provided 50 with a series of sharp, inwardly directed points 8 which are adapted to pierce the insulation of the wires to be connected. The outer edge of the ring 7 is provided 55 with a series of sharp, outwardly directed points 9 which are adapted to pierce the insulation of the wires to be connected.

with a substantially rectangular notch 8 to provide for the reception of the thread of a lamp screw shell, and the area 8 radial to said notch is bent as shown in Figs. 11 and 13 to offset the adjacent ends of the inner edge of said ring.

As best shown in Figs. 11 to 14 the ring 7 is formed in a wave-like manner to provide for engagement of the inner edge thereof at a plurality of spaced points with opposite sides and opposite walls of the thread of a lamp screw shell 10, which provides for relatively rigid support of a lamp 11 and insures intimate electrical contact between said shell and said ring. The ring 7 is preferably formed of metal which is sufficiently thick and sufficiently resilient to prevent permanent distortion thereof by insertion of a lamp screw shell.

The bottom wall of the circular recess 3 is provided with a shallow rectangular recess 12 which is adapted to receive the inwardly offset portion of a center lamp contact 13. The outwardly offset portion of contact 13 is located substantially centrally of the bottom wall of recess 3.

The inner face of base 2 is provided with a relatively shallow circular recess 14, the bottom wall of which is provided with the recesses 15, 16 and 17, the latter being adapted to receive the terminal elements 18, 19 and 20, respectively. The terminal 18 is provided with a threaded opening adjacent to each end thereof, one of said openings being arranged to receive a binding screw 21 and the other being arranged to receive the threaded end of a screw 22, the head of which abuts against the outer face of ring 7 and the shank of which penetrates alined openings in said ring and in the base 2 through the boss 5, said screw serving to hold said base, ring and terminal in assembled relation and also to provide an electrical connection between said ring and said terminal. The ring 7 is further secured to base 2 by a screw 23, the head of which is seated in a circular recess in the bottom wall of recess 14 and the threaded shank of which penetrates an opening in the base 2 through the boss 6 and threads into a threaded opening in said ring.

The terminals 19 and 20 are of like form and one end of each comprises a substantially rectangular portion which is adapted to overlie the horizontally bent foot of each of the contacts 24 and 25. The rectangular portions of the terminals 19 and 20 are provided with threaded openings located centrally thereof. The head of a screw 26 abuts the inwardly offset portion of the center lamp contact 13 and the threaded shank thereof penetrates alined openings in said contact, in the wall separating recesses 12 and 16 and in the foot of contact 24, taking into the threaded opening in the rectangular portion of terminal 19, thus holding said center lamp contact, the contact 24, the terminal 19 and base 2 in assembled relation and also providing an electrical connection between the lamp contact 13 and the terminal 19. The terminal 20 and the contact 25 are held in assembled relation with the base 2 by a screw 27, the head of which is seated in a recess in the bottom wall of recess 3 and the threaded shank of which penetrates alined openings in the wall separating recess 3 and terminal recess 17 and in the foot of contact 25, and takes into the threaded opening in the rectangular portion of terminal 20. The contacts 24 and 25 are located diametrically opposite to each other a short distance to either side of the axis of base 2, the vertically projecting

portions of said contacts being bowed toward each other intermediate their ends to provide for resilient and intimate engagement with a pair of contact blades.

The opposite ends of terminals 19 and 20 comprise substantially circular portions which are joined to said rectangular portions by narrow necks, said circular portions having threaded openings located centrally thereof and adapted to receive the binding screws 28 and 29. Suitable recesses (not shown) are provided in the bottom walls of the terminal recesses 15, 16 and 17 for the accommodation of the shanks of binding screws 21, 28 and 29.

A molded insulating cover member 30 of circular form is adapted to overlie the terminals 18, 19 and 20, said cover member having a pair of rectangular entrance passages 31 and 32 extending therethrough, the inner portions of said passages being enlarged to provide shoulders beneath which the upper ends of the contacts 24 and 25 are located to prevent fouling of the latter by the plug jacks which are adapted to cooperate therewith. The cover 30 is secured to base 2 by the screws 33 and 34, the threaded shanks of which penetrate openings in said cover and take into the tubular internally threaded elements 35 and 36. The tubular elements 35 and 36 are located diametrically opposite to each other in line with the contacts 24 and 25, the element 35 being located between the contact 24 and the periphery of base 2 while the element 36 is located between the contact 25 and the periphery of said base. Said elements are of like form, being provided at their outer ends with the shoulders 37 which are adapted to seat within shallow recesses in the bottom wall of recess 3, the tubular portions of said elements penetrating openings extending through the wall between the recess 3 and the recess 14 in base 2, the same being upset at their inner ends over the bottom wall of recess 14 to hold said elements in assembled relation with said base.

The outer face of the cover 30 is provided with an annular recess 38 which is adapted to receive an annular projection 39 on the enclosing case 40 of a refrigerator motor controller 52. The head of the screw 33 is adapted to seat within a circular recess in the bottom wall of the annular recess 38. The head of the screw 34 abuts against the foot portion of a bracket 41 and the threaded shank thereof penetrates alined openings in said foot portion and in cover 30 and takes into the tubular element 35 as aforementioned. A substantially rectangular recess is provided in the upper face of cover 30 adjacent to the periphery thereof to receive the foot portion of bracket 41, the peripheral rim 42 surrounding the recess 38 terminating at the sides of said recess to accommodate said bracket as shown in Figs. 1 and 5. The outwardly projecting portion 43 of bracket 41 is substantially parallel to the axis of the connector 1, said projecting portion being bent at an angle of substantially ninety degrees with respect to the foot of said bracket. The projecting portion 43 of the bracket 41 is provided with a threaded opening 44 for the reception of the threaded shank of a screw 45.

As shown in Figs. 2 and 4, the binding screws 21, 28 and 29 are closely grouped adjacent to the periphery of base 2. The cover 30 is provided with a relatively large opening 46 which is located substantially in alignment with the binding screw 28, the binding screws 21 and 29 being disposed on opposite sides of said opening. The wires 47, 75

48 and 49 are shown diagrammatically in Fig. 4, the same being actually brought through the opening 46 and connected to the terminals 20, 19 and 18, respectively, by the binding screws 5 29, 28 and 21; said wires being preferably combined in the form of a three-wire conductor cord.

Attachment of the connector 1 to the controller case 40 is effected by registering the passages 31 and 32 with the plug jacks 50 and 51 and 10 pressing the connector into the position indicated by dotted lines in Fig. 6 to effect engagement of said jacks with the contacts 24 and 25 in a well-known manner, as illustrated in Fig. 4. The connector 1 is rigidly secured to the case 40 by tightening of the screw 45 against the segmental ridge or projection 39.

The circuit connections of Fig. 4 are as follows:

One side of the compressor motor M is connected to line L¹, the other side being connected 20 to line L² by the conductor 47, to and through terminal 20, the resilient contact 25, contact blade 51, through the automatic temperature responsive control 52, contact blade 50, resilient contact 25 20 24, terminal 19, by conductor 48 to line L². A portion of a refrigerator box is shown schematically at 53 and a portion of a refrigerator door at 54. A normally closed switch 55 (shown schematically) is adapted to be held in open position by the door 54 when the latter is 30 closed. Upon opening the door 54 the switch 55 closes, thus completing a circuit for the lamp 11 which circuit may be traced from line L¹ through the switch 55 by conductor 49 to and through terminal 18, the screw 22, the ring contact 35 7, the lamp screw shell 10 and the filament of the lamp 11, through the center lamp contact 13, the screw 26 and terminal 19 by the conductor 48 to line L².

It is apparent from the foregoing that connection of the various electrical devices of a refrigerator to a current supply may be simply and conveniently effected by means of the afore-described connector and that the appearance of the wiring will be much neater. It is to be understood that the lamp 11 will be located within the refrigerator cabinet to be illuminated upon opening of the refrigerator door in the usual manner.

Referring now to Figs. 7 to 10, the same illustrate a connector 60, which, while differing in appearance from the connector 1, embodies the salient features of our invention.

The connector 60 comprises a two-part molded insulating casing and the contact and wiring terminal parts which will be hereinafter described. 55 The insulating casing comprises the molded members 61 and 62. The member 61 is provided with a molded-in, internally-threaded insert or nut 63 which is adapted to receive the threaded end of a screw 64. The nut or insert 63 is located 60 at the inner end of a circular recess 65 in the member 61, the wall of said recess having an integral annular flange 65a overlying said insert to retain the latter in position. The inner end of recess 66 is preferably provided with a countersink 66a to receive the head of the screw 64. Clearance openings 67 and 68 for the screw 64 are provided in the members 61 and 62, respectively, the opening 67 terminating at the insert 63 and the opening 68 communicating with the countersink 66a. The member 61 is further provided with a molded-in tubular, internally-threaded insert 69 as shown in Fig. 10. The insert 69 is adapted to receive the threaded shank of a 70 binding screw 70. Except for the inserts 63 and 75

69 in member 61, the latter and member 62 are of like form.

From the foregoing it will be apparent to those skilled in the art that the members 61 and 62 may be molded in the same die, certain mechanical parts of the die being interchangeable with other parts in well-known ways to enable the molding-in of the inserts 63 and 69.

The outer surface of each of the casing members 61 and 62 is substantially semi-cylindrical, 10 the two members forming a substantially cylindrical casing when assembled. The outer end of the casing 61, 62 is provided with an annular groove 71 which is adapted to receive a split wire ring 72, which, together with the screw 64 holds 15 the casing members in assembled relation. The inner end of the casing 61, 62 is of reduced diameter to permit entrance thereof into the recess surrounded by the segmental ridge or projection 39 on the refrigerator motor control box 52 20 shown in Fig. 6.

The inner face of the casing 61, 62 is provided with the spaced passages 73 and 74 which communicate with the longitudinal recesses 75 and 76 and are adapted to provide for entrance of 25 the plug jacks 50 and 51. The recesses 75 and 76 are adapted to receive the reflexed resilient contact members 77 and 78. Said contact members are of like form and the same are each provided with an opening to receive a lug on the terminal 30 members 79 and 80, the latter being riveted over said contact members as shown at 81 and 82 in Fig. 9 to rigidly secure said contact members to said terminal members.

The terminal member 79 is adapted to be received into the recess 83 and is provided with a threaded opening for reception of the threaded shank of a binding screw 84. The terminal 79 and the inner end of the terminal member 80 are substantially on a plane with the dividing line 40 between the assembled casing members 61 and 62. The outwardly extending portion 85 of terminal member 80 is downwardly offset from said plane at the point 86 to rest upon the ledge 87 as shown in Figs. 9 and 10. The terminal member 80 is provided with a threaded opening adjacent to each end thereof to receive the threaded shanks of binding screws 88 and 89. Recesses are provided in the casing sections to accommodate the shanks of binding screws 84, 88 and 89 50 as shown in connection with the latter at 90 in Fig. 10.

The casing 61, 62 is provided in its upper end with a wiring cavity 91 to which entrance of the necessary wires is provided by the substantially 55 elliptical opening 93. The insulating barriers 94 and 95 are formed in the casing members 61 and 62, respectively, the barrier 94 being disposed between the terminal 79 and the terminal 96, while the barrier 95 is disposed between the 60 binding screws 88 and 89 of terminal 80.

As shown in Figs. 9 and 10 the terminal 96 comprises a pair of cup washers, one being superposed upon the other, an arrangement which facilitates connection of the lamp 11 to line L¹. 65

The circuit connections of Fig. 9 are as follows:

One side of the compressor motor is connected to line L¹, the other side being connected to line L² by the conductor 97, to and through the terminal 79, the resilient contact 77, plug jack 50, through the automatic temperature responsive control 52, plug jack 51, resilient contact 78, terminal 80, by conductor 98 to line L².

As described in connection with Fig. 4 a nor- 75

mally closed switch 55 is adapted to be held in open position by a door 54 when the latter is closed. The switch 55 closes when the door 54 is opened, thus completing a circuit for lamp 11 which circuit may be traced from line L¹ to and through the terminal 96, by conductor 99 to lamp 11, through switch 55, by conductor 100, through terminal 80, by conductor 98 to line L².

The two embodiments of our invention illustrated by the accompanying drawings and described herein fulfill the stated objects in that among other features the construction of the connectors is simple, the parts thereof are so formed as to facilitate assembly thereof, and the same are arranged to provide convenient means for effecting the necessary wiring connections.

While both forms of connector may be employed to generally attain the same end, each is peculiarly adapted for use in a particular type of installation. Thus the connector 1 may be employed where the controller 52 is so located in the refrigerator that the desired illumination of the interior of the cabinet is provided if the lamp 25 is directly associated with the controller. If, however, it is more feasible or more desirable due to the location of the controller 52 or for other reasons to locate the lamp at a point removed from the controller, the arrangement illustrated 30 in Fig. 9 may be employed.

The automatic temperature responsive control 52 indicated in Figs. 4, 6 and 9 may be of the type disclosed in the pending application of Clarence W. Kuhn, Serial No. 708,804, filed January 29, 1934.

What we claim as new and desire to secure by Letters Patent is:

1. A service connector for electric refrigerators and the like comprising a pair of substantially 40 semi-cylindrical molded insulating members of like shape and dimensions, said members having pairs of complementary recesses formed therein, plug jack receiving contacts located in said recesses, wiring terminal members attached to the 45 inner ends of said contacts, one of said wiring terminal members comprising a plate having a binding screw associated therewith, the other of said wiring terminal members comprising a relatively long plate having a binding screw associated with each of the opposite ends thereof, 50 one of said insulating members having an internally threaded member attached thereto, a binding screw cooperating with said last-mentioned member, a pair of perforated sheet metal 55 members carried by said screw and respectively adapted for clamping engagement with a pair of terminal wires to provide a common electrical connection for the latter, said insulating members having complementary recesses formed 60 therein to provide a wiring cavity and a conductor passage communicating with said cavity, all of said wiring terminal members being located upon one of said insulating members and being readily accessible upon separation of 65 the latter from the other member.

2. As an article of manufacture, a plug connector comprising a pair of molded insulating members of like shape and dimensions, said members having pairs of complementary recesses formed 70 therein adjacent to the inner ends thereof, plug jack engaging contacts located in said recesses, wiring terminal members attached to the inner ends of said contacts, one of said wiring terminal members comprising a plate 75 having a binding screw in threaded engagement

therewith, the other of said wiring terminal members comprising a relatively longer plate, one end of which is attached to its associated contact and the other end of which extends toward the outer end of said connector, a pair of 5 binding screws in threaded engagement with the opposite ends respectively of said last-mentioned plate, an additional wiring terminal member comprising an internally threaded insert carried by one of said insulating members, a binding screw having threaded engagement with said insert, a pair of cup washers carried by said binding screw, complementary recesses formed in the respective insulating members and adapted to form a wiring cavity and a conductor passage 10 communicating with said cavity, all of said wiring terminal members being located upon one of said insulating members and being readily accessible upon separation of the latter from the other member, an additional threaded insert carried by one of said insulating members adjacent to the inner end thereof, a screw penetrating each of said members and having threaded engagement with said insert, said members having aligned external semi-circular grooves formed 15 therein adjacent to the outer ends thereof, and a split wire ring forcibly insertable into said grooves to assist in retaining said members in assembled relation.

3. As an article of manufacture, a plug connector comprising a pair of molded insulating members of like shape and dimensions, said members having pairs of complementary recesses formed therein, resilient plug jack engaging contacts located within said recesses, said contacts each having an arm extending rearwardly therefrom, a wiring terminal member attached to the rearwardly extending arm of each of said contacts, one of said wiring terminal members comprising a plate having a binding screw in threaded engagement therewith, the other wiring terminal member comprising a relatively longer plate having inner and outer end portions, said portions being offset in different planes relatively to each other, binding screws in 40 threaded engagement with the opposite end portions of said last-mentioned plate, said contacts and wiring terminal members being removably insertable into the aforementioned recesses in one of said insulating members and frictionally 45 engaged with the walls of said recesses to facilitate wiring of said members, said insulating members being adapted to positively retain said contacts and wiring terminal members in their proper positions when all of said parts are in 50 assembled relation, an additional wiring terminal member comprising an internally threaded insert carried by one of said insulating members, a binding screw having threaded engagement with said insert, a pair of cup washers carried by said 55 binding screw, all of said wiring terminal members being located upon one of said insulating members and being readily accessible upon separation of the latter from the other member, additional complementary recesses formed in the 60 respective insulating members and adapted to form a wiring cavity and a conductor passage communicating with said cavity, a threaded insert carried by one of said insulating members adjacent to the inner end thereof, a screw penetrating each 65 of said members and having threaded engagement with said insert, said members having aligned external semi-circular grooves formed therein adjacent to the outer ends thereof, and a split wire ring forcibly insertable into said 70 75

grooves to assist in retaining said members in assembled relation.

4. A plug connector comprising a two-part molded insulating casing adapted to be plugged onto a pair of plug jacks, said casing enclosing a pair of resilient contacts adapted for cooperative engagement with the plug jacks, a terminal member associated with one of said contacts and adapted for connection to a translating device of suitable form, a second terminal member associated with the other of said contacts, said second terminal member being adapted for connection with a suitable source of current supply, and a third terminal member, said third terminal member cooperating with said second terminal member to provide for completion of a circuit independently of said first mentioned terminal member, all of said contacts and said wiring terminal members being concealed by said two-part casing upon assembly of the latter.

5. A service connector attachment for electric refrigerators comprising a two-part molded insulating casing having a wiring cavity formed by and located between the casing parts, said casing having formed therein a conductor passage communicating with said cavity, at least three wiring terminal members located within said cavity, a pair of plug jack engaging contacts directly connected electrically and mechanically with two of said terminals respectively, said cas-

ing having recesses to accommodate said contacts, said casing also having restricted passages formed therein and communicating with said recesses to provide for insertion of a pair of plug jacks with which said contacts are adapted to cooperatively engage, one of said two terminal members and a third terminal member being adapted to provide for connection of a translating device to a source of current supply independently of the other of said two terminal members.

6. A service connector attachment for electric refrigerators comprising a longitudinally divided, two-part molded insulating casing having a wiring cavity formed by and located between the respective casing parts, said casing parts being complementally formed to provide a conductor passage communicating with said cavity, three wiring terminal members located in spaced relation to each other within said cavity, said casing parts having pairs of complementary recesses formed therein, a pair of plug jack receiving contacts located within said recesses for cooperative engagement with a pair of plug jacks, and means including two of said wiring terminal members to provide for connection of a translating device to a source of current supply independently of said plug jack receiving contacts.

GEORGE J. MEUER. 30
